 Wallace & Tiernan Company, Inc., Belleville,
 N. J., a corporation of New York

Application May 27, 1931. Serial No. 540,490

11 Claims. (Cl. 210—28)

This invention relates to diffusers for discharging gas in a finely divided state into a liquid. In the direct application of chlorin gas to water it has been the practice to discharge the gas, supplied under suitable pressure, through means, usually a finely porous wall, whereby the gas is diffused into the water in the condition of small bubbles. Difficulty has been experienced in such direct application of chlorin to water due to the formation of chlorin hydrate when the temperature of the water is as low as 40°. This chlorin hydrate takes a more or less solid form and tends to clog the minute passages of the diffuser, reducing the outflow of the chlorin gas and even entirely stopping such outflow. This results not only in reducing or entirely stopping the supply of chlorin to the water, but in case of complete stoppage, may even result in such building up of pressure within the diffuser head as to cause breakage of the diffuser wall, the wall being usually formed of porous alundum or other material not having great strength.

The principal object of the present invention is to overcome these difficulties by preventing the formation of chlorin hydrate in or on the diffuser so that in the operation of the diffuser the full flow of chlorin to the water in which the diffuser is submerged will be maintained under all temperature conditions. To this end I provide, in accordance with the invention, heating means associated with the diffuser so as to maintain the temperature of the gas as it comes into contact with the water sufficiently to prevent harmful clogging of the diffuser by the formation of chlorin hydrate. Most desirably, the heat supplied will be sufficient to entirely prevent the formation of chlorin hydrate in or closely adjacent to the diffuser. The heating means is most desirably an electric heating unit comprising a resistance wire for generating heat by the passage of an electric current through it. The diffuser is most desirably in the form of a hollow body or head with the heating unit located within it. In order to avoid destruction of the heating unit from contact to chlorin gas therewith, the unit must either be of material resistant to chlorin, such as platinum wire, or must be protected against access of the chlorin thereto. Such protection may be accomplished in various ways, as by coating the resistance wire with ceramic enamel, or, and preferably, by locating the heating unit within a tube of silver or other chlorin resistant material which extends into the diffuser head through the tube by which

the diffuser is carried and through which chlorin-gas is supplied.

Other objects of the invention are to provide a heated diffuser apparatus which, while of simple construction, shall be reliable in operation and have its parts readily accessible and which is conveniently set and removed from operating position.

A full understanding of the invention can best be given by a detailed description of a preferred embodiment thereof, and such a description will now be given in connection with the accompanying drawing which shows in axial section an illustrative apparatus according to the invention mounted on a water main partly shown in transverse section.

Referring to the drawing, there is shown at 5 a part of the wall of a water main through which the water to be purified by the diffusion of chlorin therein flows under more or less pressure. The diffuser 10, which is submerged in the flowing water in the main, is carried by a tube 11, of silver or other suitable chlorin resistant material, which extends into the water main through an opening in the wall thereof and through a suitable valve device such as a corporation cock 12. Mounted within the tube 11, is an inner tube 15 which is also of silver or other chlorin resistant material, and which extends down into the diffuser. This inner tube is of an external diameter somewhat less than the internal diameter of the outer tube 11 so as to leave between the tubes a passage 16 for the flow of chlorin gas to the diffuser. The lower end of the inner tube is closed by a plug 17 brazed into the end 90 of the tube and having a projecting threaded end portion. The upper ends of the two tubes are brazed or otherwise securely fastened in an internally bored and shouldered head block 20 which closes the upper end of the annular 95 passage between the two tubes and provides through the upper end of its bore access to the upper end of the inner tube. For supplying the chlorin gas to the annular passage 16, a supply tube 21 is connected into an opening in the head block 20 communicating with the upper end of said passage. The chlorin gas may be supplied at the desired pressure from any suitable supply apparatus in the usual manner, the supply line being provided with the usual shut-off 100 and check valves.

The diffuser 10 may be of any suitable construction for accomplishing the desired diffusion of the gas into the surrounding water, having for this purpose a wall of suitable porous chlorin re-

sistant material such as alundum. Most desirably, the diffuser, as shown, is formed by a cylindrical shell of the diffusing material clamped between a collar 25 brazed or otherwise securely attached near the inner end of the tube 11 and a cap 26 screwed on to the threaded end of the plug 17, packing gaskets 27 and 28 being provided between the ends of the diffuser shell and the collar 25 and cap 26, respectively.

10 A heating unit 30 is provided within the inner tube 15, and most desirably in the end portion of the tube within the diffuser shell, and is connected to a source of electric current by means of a cable 31 containing feed and return wires 32 and 33 and extending from the heating unit through the tube 15. The heating unit may be of any suitable construction having a resistance element for supplying heat on the passage of electric current through it. The drawing shows 20 a unit of well known construction in which a resistance wire is coiled on a core of refractory non-conducting material mounted within a metal sheath. The unit should be of sufficient heating capacity according to the size of the diffuser 25 and the amount of chlorin to be passed through the diffuser. A unit of from 25 to 50 watts capacity has been found ample for an ordinary size diffuser handling from 50 to 75 lbs. of gas per day.

30 Connected in the circuit to the heating unit is an indicating device for showing when current is flowing to the unit. Any suitable indicating device such as a galvanometer or an electric light bulb 34, as shown, may be used for this purpose.

35 To provide for convenient positioning and removal of the diffuser assembly as thus described, an extension sleeve 40 is secured by a coupling 41 to the end of sleeve 42 which carries the corporation cock 12. A stuffing box at the 40 outer end of the sleeve 40, comprising a gland 43 and packing 44 seated against a collar 45 within the sleeve 40, serves to hold the diffuser carrying tube 11 in position and to prevent escape of water from the main when the diffuser is in position and the cock 12 open, and also permits 45 the tube to be slid within the sleeve 40 and through the cock 12 to move the diffuser down into operative position or to withdraw it past the cock into the sleeve 40.

50 The diffuser assembly may thus be readily removed from or mounted operatively with relation to the main 5. In order to remove the device from the main, the head block 20 and tube 11 are drawn outward until the diffuser head is 55 drawn up into the sleeve 40 entirely beyond the cock 12, the stuffing box gland 43 being loosened, if necessary, to permit easy movement of the tube therethrough. The cock may then be closed and the coupling 41 unscrewed to disconnect the 60 sleeve 40 from the valve sleeve 42. To mount the diffuser in position within the main, the operation is reversed, that is, the sleeve 40 with the tube 11 extending through its stuffing box and with the diffuser head drawn back within the 65 sleeve, is connected to the valve sleeve 42, and then the valve is opened and the tube pushed down to carry the diffuser to the desired position within the water main.

70 With the apparatus constructed as shown, the heating unit 30 may be withdrawn from the diffuser and from the tube structure by means of the conducting cable 31, and may be returned to position within the inner tube and diffuser by lowering it or pushing it through the inner tube 75 to the desired position.

Because of the possibility of water entering the inner tube under certain conditions of use of the apparatus, it is desirable that the cable 31 and the heating unit itself shall be of waterproof construction, and under some conditions of use it 80 may, in order to prevent access of water to the inner tube, be desirable to provide a suitable removable closure for the top of the inner tube.

When the apparatus is in use, chlorin gas being supplied through the supply tube 21 and thence through the annular passage 16 to the diffuser head, and electric current being supplied to the heating unit, the temperature of the gas as it passes through the diffuser wall will, by heat supplied by the unit, be maintained so as to prevent the formation of chlorin hydrate in or at the diffuser and consequent clogging of the passages through the diffuser wall under all conditions of temperature of the surrounding water. Even when the supply of chlorin is interrupted, the supply of heat by the unit will be of advantage in heating water which seeps through the diffuser wall and backs up into the annular supply passage 16. This water coming in contact with chlorin gas within the diffuser 100 chamber and the passage 16 would, if cold, form chlorin hydrate, which would then clog the diffuser when chlorination is again started. By having the water which enters the diffuser heated, such formation of chlorin hydrate is prevented.

Suitable current control means may, of course, be provided for rendering the heating unit operative or inoperative as desired, and for varying the amount of heat generated by the unit. As 110 above pointed out, if the heating unit and feed cable are of chlorin resisting material or are otherwise protected, the double tube construction may be dispensed with. The inner tube is of advantage, however, not only for protecting the 115 heating unit and cable from the chlorin, but because it provides for convenient mounting and removal of the heating unit. It also makes a more rigid construction, so that the outer tube may be thinner than would otherwise be suitable. 120

The invention is not to be limited to the exact construction shown and to which the foregoing description has been largely confined, but includes changes and modifications thereof within the claims.

What is claimed is:

1. Apparatus for discharging gas into liquid, comprising a diffuser to be immersed in the liquid, and means for supplying heat to the diffuser adapted to maintain the diffuser at a temperature higher than that of the surrounding liquid.

2. Apparatus for discharging gas into liquid, comprising a diffuser to be immersed in the liquid, and a heating unit associated with the diffuser adapted to maintain the diffuser at a temperature higher than that of the surrounding liquid.

3. Apparatus for discharging gas into liquid, comprising a diffuser formed to provide a gas 140 chamber having a wall of porous material, and a heating unit mounted close to said wall.

4. Apparatus for discharging gas into liquid, comprising a diffuser formed to provide a gas chamber and having an enclosing wall of porous 145 material, and a heating unit within the diffuser.

5. Chlorinating apparatus, comprising a discharge device for diffusing chlorin gas into water, and heating means associated with said discharge device adapted to maintain the discharge 150

- device at a temperature higher than that of the surrounding water. 80
6. The combination with a diffuser to be submerged in water to which chlorin is to be applied, of means for supplying chlorin gas under pressure to the diffuser, and means for supplying heat to the diffuser adapted to maintain the diffuser at a temperature higher than that of the surrounding water. 85
10. Chlorin discharge apparatus, comprising a diffuser having a cylindrical porous wall, a tube by which the diffuser is carried, a tube of less diameter mounted within the carrying tube extending into the diffuser and closed at its inner end, means at the outer ends of the tubes closing the passage between the tubes, an electric heating unit within the inner tube at its lower end within the diffuser, and means for supplying chlorin gas to the passage between the tubes. 85
10. 7. The combination with a diffuser to be submerged in water to which chlorin is to be applied, of means for supplying chlorin gas under pressure to the diffuser, and an electric heating unit associated with the diffuser adapted to maintain the diffuser at a temperature higher than that of the surrounding water. 90
8. Chlorin discharge apparatus, comprising a diffuser formed to provide a gas chamber having a porous wall, an electric heating unit mounted within the diffuser, and means for supplying chlorin gas under pressure to the diffuser. 95
20. 9. Chlorin discharge apparatus, comprising a diffuser having a cylindrical porous wall, a tube by which the diffuser is carried, a tube of less diameter mounted within the carrying tube and closed at its inner end, means at the outer ends of the tubes closing the passage between the tubes, a heater within the inner tube, and means for supplying chlorin gas to the passage between the tubes. 100
30. 11. Chlorinating apparatus, comprising in combination with a water conduit, a tubular fitting connected to the conduit at an opening in the conduit wall and provided with a valve formed to leave when open a passage straight through the fitting, a sleeve detachably connected to said fitting and having a stuffing box at its outer end, a chlorin discharge device comprising a carrying tube and a diffuser carried thereby, said tube being mounted in and slidably in said stuffing box to permit the diffuser to be moved into operative position within the conduit and to be withdrawn into said sleeve, means for supplying chlorin gas to the outer end of said tube, and an electric heating unit mounted within the diffuser fed by a cable leading through said tube and from the outer end thereof. 105
